UNITED STATES PATENT OFFICE.

JOHN C. McLAUGHLIN, OF JERSEY CITY, NEW JERSEY, ASSIGNEE TO UNDERWOOD
TYPEWRITER COMPANY, OF NEW YORK, N. Y., A CORPORATION OF NEW JERSEY

TYPE-WRITING MACHINE.

953,794.

Specification of Letters Patent.

Patented Apr. 5, 1910.

Application filed January 14, 1908. Serial No. 410,738.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to typewriting and tabulating machines, and particularly to means for braking or controlling the speed of the carriage when the same is released from its letter spacing mechanism.

In a co-pending application No. 403,891, filed November 26, 1907, is illustrated one form of revolving brake which is operated by a pinion, the latter being caused by the carriage-release key to mesh with a gear provided upon the spring barrel which propels the carriage.

One of the objects of the present invention is to prevent any ill results when a tip of the tooth of the pinion accidentally catches upon the tip of the tooth of the gear. For this purpose, I provide a yielding connection between the brake frame or barrel and said release key, so that the depression of the release key may be completed in any case. Said yielding connection is preferably in the form of a spring, which acts immediately upon the release of the carriage to force the pinion into proper mesh with the gear on the carriage spring barrel.

Another object of the invention is to provide a suitable attachment for employing the aforesaid braking means in connection with the simple tabulating mechanism heretofore generally employed upon Underwood typewriting machines.

In the accompanying drawings, Figure 1 is a sectional side elevation of a portion of an Underwood typewriting machine having my improvements applied thereto; the parts being shown in normal positions. Fig. 2 is a fragmentary view of certain parts seen at Fig. 1. Fig. 3 is a view similar to Fig. 1, but showing the tabulating key depressed. Fig. 4 is a rear view of the machine illustrating many of the parts seen at Fig. 1. Fig. 5 is a diagram to illustrate the action of the aforesaid yielding connection when the tips of the teeth of the pinion ride upon the tips of the teeth of the gear wheel. Fig. 6 is a plan view to illustrate the operation seen at Fig. 5. Fig. 7 is a plan of the prin-

cipal parts of the carriage-releasing mechanism. Fig. 8 shows a sectional view of the brake barrel, showing the parts in normal positions. Fig. 9 is a part sectional view similar to Fig. 6. Fig. 10 is a view similar to Fig. 5, but showing the parts in normal positions. Fig. 11 is a view of the spring, which forms a yielding connection for the brake barrel, and which is shown in abnormal positions at Figs. 5 and 6.

The usual single tabulating key of an Underwood typewriting machine is indicated at 1 upon the forward end of a key lever 2, which is connected by a link 3 to an arm 4 projecting forwardly from a rock shaft 5, journaled upon the machine frame 6 and connected by end bars 7 to a cylindrical rod 8 and a bar 9. Column stops 10 are adjustable along said cylindrical bar 8 to engage successively a stop 11 provided upon a carriage 12, which is connected by a strap 13 to a spring barrel 14. A rack 15 is hinged at 16 upon the carriage to lift out of mesh with a pinion 17 forming part of the usual escapement mechanism. When the key 1 is depressed and the link 3 pulled down, the frame 5, 7, 8, 9, swings forwardly from the Fig. 1 to the Fig. 3 position; to enable the stops 10 and 11 to co-operate to arrest the carriage; and simultaneously an arm 18 upon the shaft 5, Fig. 2, operates a lever 19, which carries an anti-friction roll 20 to lift the rack 15 and release it from the pinion 17, so that the carriage may run along until arrested by engagement of stop 11 with the stop 10. To prevent too rapid movement of the carriage, I provide a second arm 21 upon the rock shaft 5, and depend therefrom a link 22, whose lower end is pivoted to an arm 23 extending forwardly from a rock shaft 24, the latter carrying a frame or barrel 25 containing a revolving brake mechanism. The brake is operated by a pinion 26, which at the depression of the key 1 is swung forwardly from the Fig. 1 position into mesh with a gear 27 provided upon the spring barrel 14, Figs. 3 and 5, so that during the revolution of the spring barrel, the brake is caused to operate, and hence the speed of the carriage is regulated. In order to avoid slipping or other trouble that might ensue when the tips of the teeth of the pinion ride upon the tips of the teeth of the gear, Fig. 5, I provide a yielding connection between the

brake barrel 25 and the rock shaft 24 on which it is mounted. This connection comprises a leaf-spring or yielding finger 28 secured by a screw 29 upon a hub 30 of the barrel 25. At its other end, the spring is bent inwardly at a right angle to form a finger 31. The hub 30 is recessed at 32 to admit the finger, and the rock shaft 24 is formed with a cutaway 33 which is engaged by the spring finger 31, whereby displacement of the brake barrel 25 along the shaft 24 is prevented. The cutaway 33 extends about half way through the rock shaft, and the finger 31 has opposite tips 34 to engage with the flat surface 35 which forms the bottom of recess 33, so that there can be no relative turning between the rock shaft and the hub 30 without forcing the spring 28 outwardly, Figs. 5, 6, by the action of the flat 35 upon one of the tips 34 of the spring, as seen clearly at Fig. 5. The spring is normally under tension and sufficiently strong to hold the barrel 25 in its proper relation with the shaft 24 under ordinary circumstances; but it will yield when the teeth tips engage, as at Fig. 5, to permit the completion of the carriage releasing movement of the tabulator key 1; and during the subsequent revolution of the barrel 14 the teeth 30 of the pinion 26 will be forced into proper mesh with the teeth of the gear 27.

The pinion 26 is fixed upon a shaft 36 journaled in the barrel 25 and carrying a cross arm 37, from which depend pivoted weights 38, each having an arm 39 to press up against a plate 40 when the weights 38 swing out by reason of centrifugal force. The plate 40 presses a friction washer 41 against the top or cap 42 of the barrel, 40 thereby retarding the movement of the pin-

ion 26, gear 27 and spring barrel 14, and hence of the paper carriage 12.

Having thus described my invention, I claim:

1. In a typewriting machine, the combination with a power-driven carriage and an escapement mechanism therefor, of a key having means to release the carriage, a rock shaft operated by said key, a revolving brake carried by said rock shaft and having a pinion swung by said rock shaft into engagement with a rack connected to the carriage, and a spring secured upon a hub of a barrel that carries the brake, the rock shaft being cut away to form a cam, and the spring having a clip to engage the cam and maintain the barrel yieldingly against rotation independent of the rock shaft.

2. In a typewriting machine, the combination with a power-driven carriage and an escapement mechanism therefor, of a key having means to release the carriage, a rock shaft operated by said key, a revolving brake carried by said rock shaft and having a pinion swung by said rock shaft into engagement with a rack connected to the carriage, and a spring secured upon a hub of a barrel that carries the brake, the rock shaft being cut away to form a cam, and the spring having a clip to engage the cam and maintain the barrel yieldingly against rotation independent of the rock shaft; said clip fitting in the cutaway in the rock shaft and preventing longitudinal movement of the barrel upon the rock shaft.

JOHN C. McLAUGHLIN.
